UNITED STATES PATENT OFFICE.

HERBERT H. ILLCH, OF NEW YORK, N. Y.

DESIGN FOR A GLARE-SCREEN.

49,354.

Specification for Design.

Patented July 11, 1916.

Application filed September 24, 1915. Serial No. 52,529. Term of patent 7 years.

To all whom it may concern:

Be it known that I, HERBERT H. ILLCH, a citizen of the United States, and a resident of the city of New York, borough of Manhattan, in the county and State of New York, have invented a new, original, and ornamental Design for a Glare-Screen, of which the following is a specification, reference being had to the accompanying drawing, forming part thereof.

Figure 1 is a perspective view of the rear side of the glare screen; and Fig. 2 is an elevation of the front side thereof.

I claim:

The ornamental design for a glare screen, as shown.

HERBERT H. ILLCH.
